United States Patent Office.

FRANKLIN H. BROWN, OF CHICAGO, ILLINOIS, ASSIGNOR TO HIMSELF,
EDWARD F. PEUGEOT, AND LEMUEL H. FLERSHEIM, OF SAME PLACE.

Letters Patent No. 70,072, dated October 22, 1867.

IMPROVEMENT IN MACHINE FOR MAKING BASKETS.

The Schedule referred to in these Letters Patent and making part of the same.

TO WHOM THIS MAY CONCERN:

Be it known that I, FRANKLIN H. BROWN, of the city of Chicago, in the county of Cook, and State of Illinois, have invented a new and useful Machine for Weaving Basket-Tops and Bottoms, and similar work; and I do hereby declare that the following is a full and exact description thereof, reference being had to the accompanying drawings, and letters of reference marked thereon, making a part of this specification, in which—

Figure 1 is a top view of my invention.

Figure 2 is a vertical section of my invention.

Figure 3 is a side view of the vibrating apron or weaving device that carries the filling and operates the radially projecting pieces forming the top or bottom.

Figure 4 is a view of the rod O and its connections, which, when in their proper places, crowd down or pack the filling to the desired form.

Figure 5 is a side view of the cam Z.

My invention consists in an automatic machine, used more especially for the purpose of weaving basket-tops and bottoms, or similar kinds of work.

Construction.

To enable others skilled in the art to make and use my invention, I will describe the method of its construction and operation.

L represents the socket, which is attached to the frame A. B is a vertical shaft, revolving in socket L, to which various parts of the machine are attached. D is a round, flat ring, having evenly-spaced slots 10; as shown in fig. 1, and is attached, by means of brackets I, to shaft B. Y represents a cup, with slots 10', to correspond with slots 10 in ring D, as shown in fig. 2. Q are upright rods, whose upper ends pass through slots 10, and are attached to pieces g, the lower ends being loosely connected to rods O, which lie nearly horizontal, and pass through slots 10' in cup Y. The rods O are bent, as shown in figs. 2 and 4, so that when in position the end inside of the cup stands in a vertical position. E represent forms made of spring material, one end of which is attached to piece K; the other ends pass loosely through rods O and slots 10'. F is the driving-shaft. S S are pulleys, communicating motion to the screw C. G is a cam, which is moved back by screw C and its connection J. H is a stationary cam, its office being to return the pieces g and rods O to their original positions, after they have been forced forward by means of the cam G. 4 is a standard, to which the holder 3 is attached. 1 is a rod, to which the cam Z is rigidly attached. P is the apron, which is rigidly attached to rod 2. P' is a part of the apron, which is made to vibrate by means of hinge g, in connection with pitman j and wheel k. Rod 7 is a support and axle to wheel k. M is an arm attached to the frame, and passing over to the centre of shaft B, as clearly shown in fig. 2. The set-screw m is used to confine the material or frame of the work to be completed. f and f' are mitre-gears, communicating motion to shaft B and its attachments by means of driving-shaft F.

The nuts N, as shown in fig. 4, are set in a desired position on rods O by means of screw n, which determine the distance that rods O are to move. Thus, if the nut N be placed as shown in fig. 4, then, when the pieces g and rod Q move forward the rod O does not move until the rod Q comes in contact with the nut N; but if the nut N be placed as shown in the dotted lines in fig. 4, then the rod Q, coming immediately in contact with nut N, the rod O is set in motion at once, and moves as far as the slide g and rod Q are moved. The nut N, when set at equal distances on rods O, will pack to a round form; when set at irregular distances, then they will pack to an irregular form. w is a washer, to keep rod Q steady. t is a stationary head on rod O, to prevent rod Q from slipping off. 8 is the willow or filling, which is fed through an opening in the end of apron P, as shown in fig. 3. V is a skeleton, or foundation, of a top or bottom, into which the filling 8 is woven.

Operation.

The skeleton or foundation of a top or bottom is placed upon shaft B, and is clamped to that position by set-screw m. The end of filling 8 is fed through apron P a short distance. Motion is now applied to driving-shaft F, which revolves the ring D, cup Y, and the skeleton or foundation of the work to be completed. Wheel

k, resting upon ring D, now revolves by friction, which causes the part of apron *P'* to vibrate, as shown in fig. 3, allowing the skeleton V, or foundation of the work V, as shown in fig. 3, to pass alternately over and under the apron P, and filling 8. The cam G, through its connection J, with screw C, will move back regularly the width of the filling at each revolution of the ring D, until the work is completed. When completed, remove the work, then raise spring J out of screw C, and slide the cam G back to its original position. Now all is ready to repeat.

Having thus fully described my invention, what I claim, and desire to secure by Letters Patent of the United States, is—

1. The arrangement of forms E, radiating from the shaft B, in combination with packing device O, as and for the purposes specified.
2. The arrangement of ring D, in combination with cams H and G, slides *g*, and rods Q, as and for the purposes set forth.
3. The arrangement of cup Y, in combination with shaft B and rods O, as and for the purposes specified.
4. In a machine for weaving baskets, the arrangement of arm M, shaft B, and set-screw *m*, as and for the purposes set forth.
5. In a machine for weaving baskets, the vibrating apron *P'*, as set forth and for the purpose specified.
6. The adjustable nut N, in combination with the rods O and Q, as and for the purposes set forth.

FRANKLIN H. BROWN.
